(57) **CLAIM**

The ornamental design for a nail nipper with catcher, as shown and described.

DESCRIPTION

FIG. 1 is a rear perspective view of a nail nipper with catcher showing my new design;

FIG. 2 is a front view thereof;

FIG. 3 is a rear view thereof;

FIG. 4 is a right side view thereof, the left side being a mirror image;

FIG. 5 is a top view thereof; and,

FIG. 6 is a bottom view thereof.

Broken lines in the drawings depict portions of the nail nipper with catcher that form no part of the claimed design.

1 Claim, 6 Drawing Sheets
